UNITED STATES PATENT OFFICE.

MELANCTHON HELI ODELL, OF CINCINNATI, OHIO.

KEYBOARD.

SPECIFICATION forming part of Letters Patent No. 786,669, dated April 4, 1905.

Application filed August 10, 1904. Serial No. 220,206.

To all whom it may concern:

Be it known that I, MELANCTHON HELI ODELL, a citizen of the United States, and a resident of Cincinnati, in the county of Hamilton and State of Ohio, have invented a new and Improved Keyboard, of which the following is a full, clear, and exact description.

The invention relates to pianos and organs; and its object is to provide a new and improved keyboard in which the keys are not liable to stick on account of the tightening of the bushing on the balance and guide pins caused by the swelling of the wood carrying the bushing and at the same time allowing the use of any kind of fall-board, as all cross-rails, key-binders, and like devices are entirely dispensed with.

The invention consists of novel features and parts and combinations of the same, as will be more fully described hereinafter and then pointed out in the claims.

A practical embodiment of the invention is represented in the accompanying drawings, forming a part of this specification, in which similar characters of reference indicate corresponding parts in both views.

Figure 1 is a sectional perspective view of the improvement, and Fig. 2 is a cross-section of the same on the line 2 2 of Fig. 1.

On the frame A of the keyboard are arranged the usual front rail B, the intermediate rail C, and the back rail D, on which latter normally rest the rear ends of the keys E, mounted to swing on the balance-pins F, resting on the intermediate rail C, the front ends of the keys being guided by the guide-pins G, rising from the front rail B.

Each guide-pin G extends through a closely-fitting bushing H, of felt or other similar suitable material, and this bushing is secured to a wooden support I, fitted in a recess in the body of the key E and glued or otherwise secured thereto, so as to practically form an integral part of the key.

Each balance-pin F is engaged at its sides and near the top thereof by a bushing H', similar to the bushing H, and likewise at-

tached to a wooden support I', similar to the support I, and secured to the body of the key E to form a part thereof, the same as the support I. As shown in the drawings, the support I forms part of the bottom portion of the key, while the support I' is arranged on the top thereof, and each support is preferably forked at one end to receive the bushing H or H' at the inner faces of the fork members, the opening between the fork members registering with the apertures E' and E'', formed in the key-body, and in which apertures extend the guide-pins G and the balance-pins F freely—that is, without touching the walls of the said apertures.

Each of the wooden supports I and I' has its grain arranged at angles to the grain of the body of the key E, and each wooden support is preferably of the composite type—that is, made of a plurality of superimposed layers of wood glued together, the grains of adjacent layers crossing each other to render the support non-shrinkable in itself and non-shrinkable relative to the body of the key E.

By having the bushings mounted on the non-shrinkable supports it is evident that the key is not liable to stick on the balance-pin F or on the guide-pin G, and hence the key is always kept in proper position and is in proper condition to yield to the touch of the player.

The device is very simple and durable in construction and can be cheaply manufactured and readily applied to the white as well as to the black keys of the keyboard.

Having thus described my invention, I claim as new and desire to secure by Letters Patent—

1. A key for a keyboard, having a bushing, and a cross-grain wooden support for the bushing and attached to the key.

2. A key for a keyboard, having a body provided with a recess, a cross-grain wooden support fitted into the said recess and secured in position thereon, and a bushing carried by the said cross-grain support.

3. A keyboard provided with an intermediate rail carrying balance-pins, and keys mounted to swing on the said balance-pins, each key

having a cross-grain support and a bushing carried by the said support and engaging the corresponding balance-pin.

4. A keyboard provided with a front rail, 5 guide-pins on the said front rail, and keys having cross-grain supports and bushings on the said supports, engaging the said guide-pins.

In testimony whereof I have signed my name to this specification in the presence of two subscribing witnesses.

MELANCTHON HELI ODELL.
